UNITED STATES PATENT OFFICE.

WILLIAM GEGENHEIMER, OF BALDWIN, AND ERNEST E. BARNEY, OF PORT WASHINGTON, NEW YORK.

APPARATUS FOR OFFSET PRINTING.

Application filed August 29, 1924. Serial No. 734,966.

This invention relates to an apparatus for indirect, three member of offset printing and it has for its object to provide means whereby a plurality of films of ink, color or dye are transposed from the plate to the blanket, the result being that the deposit from the blanket to the paper, fabric or other body receiving the printing is very much greater than heretofore possible in offset printing. For example, the usual indirect, three member, offset black printing appears gray or impoverished when compared to work done by direct, two member printing, because of certain reasons which are pertinent to an understanding of the present invention.

In indirect, three cylinder, planographic, relief reproductive processes, such as lithography, metalography, offset, rotary, and also such processes using plates etched or otherwise wrought in relief, or other kindred processes, the chemical antipathy between oil and water is customarily utilized, and the work, design, pattern or text from which reproductions are to be taken is laid down on, above or in below the surfaces in substances having a greater affinity for oils, fats and greases than for water and other chemicals possessing similar attributes, this work then being charged with sufficient additional ink, dye or pigments in oils or binders to transfer its design from the primary to a second cylinder, customarily covered with a rubber blanket or other slightly yielding or elastic composition or surface, which ink or color this secondary cylinder in its turn re-transfers to the third member or cylinder carrying the material on which reproductions are wanted, conducted to contact by this third cylinder.

We have found that there is not, under all conditions, a sufficient affinity between the inked designs on the primary or plate cylinder and the surface of the secondary or blanket cylinder for the latter to accept films of ink in sufficient volume, at a single inking from the primary surface to enable it to, in its turn, lay sufficient of that deposit onto the sheet to be printed to give sufficient density or covering qualities to reproduce as desired.

In the effort to obtain a sufficient-to-print deposit of ink, it is customary to distribute by rolling contact, repeated films of ink onto the primary surface by passing over that surface one, two, three, four or more rollers, each in its turn depositing a modicum of ink onto the primary surface.

But this has not resulted in the most desired results, because, as we have discovered, no means is thereby provided for adequately re-depositing this ink from the primary to the secondary surface other than by means of a single contact between the primary and the secondary. Between these latter two, there is less affinity for inks, dyes or colors than there is between the patterns on the primary cylinder and the form rollers carrying inks thereto from their source in the ink-fountain or other means of replenishing inks, dyes or color as it is being necessarily applied.

Obviously, there is a closer affinity between identical substances than between differing ones, and, as but a single contact or revolution of inking between the primary surface and the secondary surface is but offering or seeking affinity and cohesion between two differing substances, ink and rubber, customarily, it is proposed by the present method and apparatus to secure greater affinity, not by still further piling up of ink on the primary cylinder but by overcoming the usual effect of antipathy between inks, dyes and colors and the rubber, fabric, composition or other surface of the secondary cylinder by repeated inkings of ink on ink, chemical on the same chemical, from the primary to the secondary surface. The second inking deposits a film of ink onto a film of ink, for which it has a greater affinity than in the first inking which deposits a film of ink onto a rubber or other surface hostile to such reception or application.

In the indirect, three member, offset press and process, the method is achieved by effecting two or more rotations of the plate and blanket cylinders during two rotations of the impression, or paper-carrying, or feed cylinder, two functionings of the inking to one functioning of the printing, one rotation of the feed cylinder being idle, it being retracted. Any suitable means can be provided for effecting this result. For example, the feed—or impression cylinder carrying material to be printed upon—cylinder may be geared with the plate and blanket cylinders so as to be simultaneously rotated therewith, but may be given a bodily movement away from the blanket cylinder during one or more of the ink-receiving rotations of the latter and again given a bodily movement, after being inked to the desired degree, to come into printing position contact with the material to be printed.

In the drawings we have illustrated diagrammatically a typical rotary offset press.

Figure 1 represents in diagrammatic form a sectional side elevation of said press and

5 Figure 2 represents in plan, and somewhat diagrammatically, means for effecting a bodily movement of the impression-cylinder or feed-roller while maintaining it in mesh with the plate and blanket rollers or cylinders.

10 In the drawings, A represents the impression or feed cylinder, B the blanket cylinder and C the plate cylinder, it being understood that the said cylinders are geared together to rotate at the same speed. D represents inking rollers connected by the riders E and intermediate rollers F, to the distributing drum G for the ink. K represents the ink vibrator, J the usual vibrator, M the water distributor and L the damping rollers. The feeding board is indicated at P.

15 The impression cylinder or feed roller A is mounted in the frame of the machine in any suitable manner, for bodily movement, the projecting ends of its shaft 2 being connected to a yoke arm 4 which extends over a rotary cam-disc 5 having a cam groove 6 entered by a pin 7 on the yoke. The cam groove 6 is designed in accordance with the number of rotations desired in the plate and blanket 20 cylinders, relative to an effective movement of the feed cylinder. The cam groove 6 is also so designed that the bodily movement imparted to the feed cylinder A is insufficient to withdraw its gears from mesh with the gears of the blanket cylinder. In other words, the action of cam 5 is to periodically move feed cylinder A out of co-operative position relative to blanket cylinder B yet the feed cylinder continues its rotation, while 25 the actual feeding in of material is suspended so far as printing contact is concerned.

30 During the idle or unproductive rotations of the feed cylinder, the plate and blanket cylinders are rotated to deposit two or more 40 films of ink upon the blanket cylinder, the more willing reception by the blanket of the plurality of films being due to the affinity of ink for ink, whereas in the old method the massing of ink upon the plate cylinder and the rotation of that cylinder but once for each 45 printing operation of the blanket cylinder merely resulted in the transfer to the blanket cylinder of an amount of ink substantially 50 fixed by the low surface affinity for ink possessed by the blanket, which as hereinbefore

stated, is inadequate. Any attempt to increase this quantity takes the process outside the realm of printing and becomes mere mechanical smearing.

55 We have above described our preferred method of operation. However, it will be understood that the method may also be carried out by rotating the plate and blanket cylinders a greater number of times than the active feeding movements, that is to say, printing movements of the gripper, impression or feed cylinder. Thus, the plate and blanket cylinders might be rotated five times to four printing operations, and the result would be a more adequate deposit of ink upon the 60 material receiving the latter, and yet the plate and blanket cylinders are not given, in this instance, two or more rotations to a single active rotation of the feed cylinder. The reason for the practicability of this modified 65 method is that when the plate cylinder delivers to the blanket cylinder two or more films of ink, the blanket cylinder will not deposit all of that ink upon the paper, but sufficient 70 remains to receive, by the affinity of ink for ink, a greater quantity of ink from the next deposit from the plate cylinder than would be the case had the plate initially deposited a single film upon the blanket cylinder followed by the impression of that blanket 75 cylinder upon the paper, which would exhaust or substantially exhaust that deposit.

80 It will be understood that the press illustrated in the drawing, and the means for causing the relative periodic inaction between 85 the blanket cylinder and the impression or feed cylinder are merely illustrative, inasmuch as the principle of the invention may be applied to widely different apparatus, what we claim and desire to secure by Letters 90 Patent being as follows,—

95 In an apparatus for offset printing, a plate cylinder, a blanket cylinder and an impression cylinder, means for rotating said cylinders and means for moving the impression 100 cylinder out of operative position relatively to the blanket cylinder and for holding the impression cylinder in an inoperative position whilst the plate cylinder is offsetting a plurality of superposed films of uni-color ink 105 upon the blanket cylinder.

110 In testimony whereof, we have signed our names to this specification.

WILLIAM GEGENHEIMER.
